PHOTOELECTRIC CELL

Application filed July 2, 1927. Serial No. 203,023.

My invention relates generally to the art of translating variations of ionization effects into electrical impulses and in particular to the control of an impedance in accordance 5 with ionization phenomena.

The invention is based on the discovery that when an ion is initiated or excited within certain substances of requisite thickness, notably dielectrics or other materials of low 10 specific conductivity and further, when the substance is subjected to considerable electrical stress, the medium through which the ion travels at high velocity gives rise to an augmentation of the number of charged particles. The accumulative action effects a general movement of ions toward one of the electrodes and results in a greatly magnified space current with abrupt reduction of impedance to produce amplification of the 15 pulse originally exciting the single ion. The original impulse may be energy derived from any physical phenomenon such as light, heat, electron bombardment or other electrical effects.

20 The primary object of my invention is to translate energy impulses into electrical undulations. Another object is to provide an impedance, the magnitude of which changes in response to variations of an exciting force. Other objects and features will be apparent as the specification is perused in connection with the accompanying drawing which illustrates a preferred embodiment.

In the figure, the impedance in question 35 comprises a sheet or layer 1 of suitable material interposed between electrodes 2-2. The material may comprise a coating of linseed oil, solidified by baking or a thin layer of bakelite or other phenolic condensation 40 product having thickness preferably below 10 mu or .01 mm. In case ionization is initiated by light impinging on the surface of the solidified mass, the latter should preferably include light sensitive material as sulphur in its natural state or salt previously activated by X-rays. This ingredient may be incorporated by way of admixture or condensation and may be uniformly distributed 45 throughout the body. In order that the sensitive product may be presented to the direct

action of the rays, one of the electrodes, the upper in the figure, preferably should be permeable to light, e. g. by beating gold, silver, or similar ductile metal very thin or as a coat formed integral with the dielectric by 55 any of the well-known sputtering or bombardment processes. The ionizing source is indicated at 5.

The operation of the device described above will be apparent from a consideration of the 60 following discussion. In practically all substances a number of free ions exist. These ions are also in constant motion. The average distance through which an ion travels before it collides with an atom or molecule of 65 the substance in which it occurs is called the mean free path of the ions in that substance. If a sufficient potential gradient exists through that substance an ion in falling 70 through that potential gradient for a distance equal to its mean free path acquires sufficient kinetic energy to ionize the atom or molecule with which it collides. If, however, the potential gradient is not sufficiently large 75 no ionizing collisions will occur. When a sufficiently large potential is impressed across 80 a substance so that ionizing collisions do occur the number of charged particles liberated by accumulative ionization within the body due to each original free ion is in the ratio of 85 2 to the exponent D/λ where D is the thickness of the material between the point at which the free ion originates and the surface of the material to which it is attracted by the ionizing potential and λ is the mean free path of 90 the ion in the material. Thus it is apparent that if D is very large as compared with λ the number of charged particles created is quite enormous and would result in the passage 95 of very large currents through the substance. If however D is merely several times larger than λ , the number of charged particles created bears a direct relation to the number of original free ions but is still within a reasonable value. The number of free ions in the 100 substances of low conductivity such as those with which the applicant is dealing is so small as to be practicably negligible. If, however, in accordance with the description above, D is very large with respect to λ , the number of

charged particles created even by this negligible quantity of free ions is sufficient to cause very large currents to pass through the substance when an ionizing potential gradient is impressed on that substance. The passage of such large currents tends to destroy the insulating substance and is the reason why normally insulating substances break down when a sufficiently large potential is impressed across them. If, however, the thickness is of the order of several times that of λ , the number of charged particles liberated by accumulative ionization due to the passage of an originally free ion is of such a value that the current passing through the substance due to these particles is within a reasonable value.

From the foregoing, it will be evident that when a wave of light frequency passes through the translucent electrode and impinges on the sensitive layer, there is created an action within the layer setting free one or more charged particles which are electrostatically propelled toward the other electrode under the influence of the voltage gradient established by high potential source 3 (e. g. 3000 to 5000 volts). For every ion dislodged in this manner, there is liberated by accumulative ionization within the body, a large number of charged particles in the ratio of

$$\frac{D}{\lambda} \text{ (two to the exponent } D/\lambda \text{) where } D \text{ is the}$$

thickness of dielectric, and λ is the mean free path of ions in the dielectric or material of low specific conductivity. Since the number of free ions within the dielectric itself is negligible, it will be seen that the number of charged particles originating at the light sensitive layer are considerably greater than any free electrons which may exist within the dielectric. It is apparent that as the intensity of light is varied, the magnitude of space current undergoes a change commensurate with said ratio, hence amplification of the light wave variation is obtained in terms of current undulations which may be transferred through transformer 4 to a load circuit for any desired purpose.

Obviously this invention offers marked advantages over photo-electric cells of the gas tube type. The device is much more rugged and far less subject to breakage. The light is not required to pass through a glass wall and is therefore not subjected to the absorptive action of glass upon the light radiation, particularly of the shorter wave-lengths. The light waves (or electrons) are incident directly upon the electrode and may even permeate the dielectric material at least through a part of its thickness thereby giving rise to cumulative ionization which is far more effective to produce amplification than in the case of the ordinary gas-tube cell.

Various ways of forming the thin films of dielectric or poorly conducting material are

described in my copending applications Serial No. 65,262, filed October 28, 1925; Serial Nos. 109,213 and 109,214, filed May 15, 1926; Serial Nos. 160,771, 160,772, filed January 12, 1927 and Serial Nos. 168,448, 168,449 and 168,450, filed February 15, 1927 which are incorporated herein by reference.

I claim:

1. A light sensitive electrical device comprising an insulating layer having a thickness not greater than 10 mu, a photo-electrically active substance distributed through said insulating layer and a pair of electrodes supporting said layer, at least one of said electrodes being transparent to light. 75

2. In an electrical device, two electrodes spaced by an insulating medium whose thickness is not greater than 10 mu and means associated with said insulating medium to liberate electrons by photo-electric action. 80

3. An electrical apparatus comprising two metallic sheets, at least one of said sheets being transparent to light and a coating therebetween comprising an insulating condensation product impregnated with photo-electric material. 85

4. An electrical device comprising two metallic sheets, at least one of said sheets being transparent to light, and a layer of insulating material having a thickness not greater than 10 mu and impregnated with photo-electric substances. 90

5. A light sensitive electrical device, comprising an insulating layer having a thickness not greater than the order of several times the mean free path of ions in that layer, and means associated with said insulating layer to liberate electrons by photo-electric action. 100

6. In an electrical device, two electrodes spaced by an insulating medium whose thickness is not greater than the order of several times that of the mean free path of ions in that medium, means associated with said insulating medium to liberate electrons by photoelectric action, and a source of potential impressed across said electrodes, said potential being sufficiently great to cause said electrons to have ionizing collisions with atoms of said medium. 105

7. A photo-cell, comprising a pair of electrically conducting terminal layers having extended surfaces disposed adjacent to each other and separated from each other with an insulating junction layer of negligible thickness, said insulating junction layer embodying substance adapted to pass electrons from one conducting layer to the other under photo-electric action, one of said conducting layers being transparent. 115

8. A photo-cell, comprising a pair of electrically conducting terminal layers having extended surfaces disposed adjacent to each other and separated from each other with an insulating junction layer of a thickness not greater than 10 mu, said insulating junc- 120

tion layer embodying substance adapted to pass electrons from one conducting layer to the other under photo-electric action, one of said conducting layers being transparent.

- 5 9. A photo-cell, comprising a pair of electrically conducting terminal layers having extended surfaces disposed adjacent to each other and separated from each other with an insulating junction layer of negligible thickness, one of said conducting layers being transparent, and means associated with said insulating junction layer to liberate electrons by photo-electric action and pass a discharge from one conducting layer to the other.
- 10 15 Signed by me at Cambridge, Massachusetts this 7th day of June, 1927.
